UNITED STATES PATENT OFFICE.

FOIRE RICCIARDELLI, OF JERSEY CITY, NEW JERSEY.

PERCOLATOR-SUPPORT.

1,180,881.

Specification of Letters Patent. Patented Apr. 25, 1916.

Application filed November 12, 1914. Serial No. 871,710.

To all whom it may concern:

Be it known that I, FIORE RICCIARDELLI, a citizen of the United States, residing at Jersey City, in the county of Hudson and State of New Jersey, have invented a certain new and useful Improvement in Percolator-Supports, of which the following is a specification.

I will first describe my improvement in detail and then point out the novel features in the claims.

In the accompanying drawings Figure 1 is a side elevation, partially in section, of a percolator support embodying my improvement; Fig. 2 is a sectional view taken through the plane of the dotted line 2—2, Fig. 1; and Fig. 3 contains partial detail views of parts of a percolator supported by my improvement.

Similar letters of reference designate corresponding parts in all the figures.

A designates a receptacle shown as provided with a downwardly tapering extension α . The lower end of this extension α is shown as provided with a shoulder α' . A fabric, as B, suitable for straining or filtering purposes, may be tied around the shoulder α' .

C designates a tube shown as funnel flared at its upper end. The extension α may be fitted into said funnel flared portion of the tube C. The funnel flared portion of the tube C may be provided with flanges or projections c, and a packing, of cork or other suitable material, may be provided to effect a tight jointure between the extension α and the tube C.

D designates a receptacle or kettle shown as provided with a flaring neck as d. The tube C is shown as inserted into this receptacle or kettle D and a packing, as c', of cork or other suitable material, may surround the exterior of the funnel shaped portion of the tube C, where the funnel shaped portion of the tube C fits into the receptacle or kettle D, so as to effect a tight jointure between the receptacle or kettle D and the funnel shaped portion of the tube C. The receptacle or kettle D is shown as provided with a shoulder, as d' at the upper end of its neck d.

My support for a percolator as thus made will now be described.

E designates a handle shown as provided with a two-part collar e e', adapted to encircle the neck d. The part e' is hinged at

e^2 to the part e which is rigid with the handle, and a clasp, as e^3 , is shown as provided for locking the parts together and clamping them around the neck d. The hinged part e' is shown as provided with a teat e^4 , adapted to fit into a recess e^5 . Inside the collar e e' I may, if desired, provide a packing, as e^6 , of cork or other suitable material. To place the handle E in position around the neck d the hinged part e' may be thrown aside and then brought around into contact with the neck d, and the clasp e^3 then pushed into such position that it will lock the hinged part e'. 70

e^7 designates an opening in the handle into which a pin f at the upper end of an upright, as F, may be inserted. The pin may be screw threaded, and a cap or nut, f', screw threaded on its interior, may be provided, to fit thereover. The upright F may be suitably secured to a base, as G. 75

The contents of the receptacle or kettle D may be heated in any desired manner. In the drawings I have shown a reservoir H for holding alcohol, oil or other desired liquid. This reservoir H is shown as resting on the base, and provided with a burner h.

The fabric B may, of course, be held in place without tying, by merely pressing the extension α into the funnel shaped portion of the tube C, allowing sufficient of the fabric to be held between the extension α and that part of the funnel shaped portion 90 of the tube C which surrounds the extension α .

The receptacle A may, if desired, be provided with a cover.

In the use of the percolator pulverized coffee or other material will be placed in the receptacle C and fall to the lower end thereof and rest on the strainer or filterer, as B. Water intended for use in making the brew will be placed in the receptacle or kettle D.

In use the collar e e' of my improved support is locked around the neck d and the handle E then placed on the upright F by inserting pin f at the upper end of the upright F into the opening e^7 of the handle E. If it be desired to use a cap, as f', said cap is placed in position on that part of the pin f which extends beyond the handle E. When desired the receptacle or kettle D may be turned to one side by merely turning the hand grip E' of the handle E, 110

and, indeed, the intensity of the heat to which the contents of the receptacle or kettle D is subjected, may, in a measure, be regulated in this manner.

5 When it is desired to serve the contents of the receptacle or kettle D the receptacle A and tube C are removed and the handle E swung aside so that the kettle is moved from over the flame, then the cap f' (if it be employed) is removed, and finally the operator with the hand grip of the handle still in her hand, lifts it off the pin f and utilizes it to raise and carry the kettle to the point of use without putting her hand 10 upon it at all. There she may turn the handle so as to tip the kettle and pour out 15 its contents as may be desired.

I have thus specifically described the percolator with which this improved support 20 is to be used, for the reason that the kettles thereof are made of glass or plain metal, and are always hot when removed from a position over the flame. It will be observed from Fig. 3 that the parts e and e' of the 25 collar are of channel-iron with their open sides facing toward the kettle's neck d, and therefore this channel serves to retain the packing e⁶ whose inner face projects slightly beyond the edges of the channel-iron as 30 shown in this view and comes into contact with said neck. Thereby a neck of glass will not be crushed, even if the parts of the collar were drawn very closely together by 35 the clasp, because the edges of the channel-iron will at no point come into contact with said neck. Moreover the outstanding shoulder d' at the upper end of the neck overlies the collar and prevents the neck from slipping out of the collar, even if the 40 latter were not clasped very tightly around it. Therefore it will be seen that the specific construction of this support is adapted especially to percolators of this kind.

What I claim as my invention and desire 45 to secure by Letters Patent is:

1. The combination with a kettle having a neck provided with a shoulder around its upper end; of a base, an upright rising from the base, a handle having a hand grip at 50 one end and a collar at its other end adapt-

ed to encircle said neck beneath its shoulder, and a pivotal support between the upright and an intermediate point on the handle whereby the latter may be moved to swing the kettle horizontally into and out of position above the base at will, for the purpose set forth. 55

2. The herein-described percolator support comprising an upright having a pin projecting vertically from it and threaded 60 at its upper end, a horizontal handle having an opening through its mid-length removably and pivotally mounted on said pin, a hand grip at one end of the handle, a collar at the other end thereof composed of 65 two parts movably connected with each other, and a nut removably mounted on the threaded upper end of the pin above said handle, for the purpose set forth.

3. The herein-described percolator support comprising a base, an upright rising therefrom and having a pin projecting vertically from its upper end, a handle having an opening through it removably and pivotally mounted on said pin, a hand grip at 70 one end of the handle, and a collar at the other end thereof composed of two parts whereof one is secured to the handle and the other is hinged to the first part with its free end adapted to lie against the handle, and a clasp for holding said end in 75 place. 80

4. The combination with a friable receptacle having an upstanding cylindrical neck; of a support therefor including a 85 base, an upright, a handle pivotally carried by said upright, a two-part collar of channel-iron whereof one part is rigidly carried by one end of the handle and the other part is hinged at its outer end to the first 90 part with its inner end adapted to lie against the handle, a clasp slidably mounted on the handle and adapted to embrace such inner end, and packing within the channels of both parts, for the purpose set 95 forth.

FIORE RICCIARDELLI.
